(57) **CLAIM**

The ornamental design for beverageware, as shown and described.

DESCRIPTION

FIG. 1 is a perspective view of a first embodiment of beverageware showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is an exploded view thereof;
FIG. 9 is a perspective view of a second embodiment of beverageware;
FIG. 10 is a front elevation view thereof;
FIG. 11 is a rear elevation view thereof;
FIG. 12 is a left side elevation view thereof;
FIG. 13 is a right side elevation view thereof;
FIG. 14 is a top plan view thereof;
FIG. 15 is a bottom plan view thereof; and,
FIG. 16 is an exploded view thereof.
The oblique shade lines in FIGS. 9-16 show transparency or translucency.
